(57) **CLAIM**

The ornamental design for a chair as shown and described.

DESCRIPTION

FIG. 1 is a perspective view of a chair according to an embodiment of the design shown in a first position.

FIG. 2 is a front view of the chair of FIG. 1 shown in the first position.

FIG. 3 is a rear view of the chair of FIG. 1 shown in the first position.

FIG. 4 is a first side view of the chair of FIG. 1 shown in the first position.

FIG. 5 is a second side view of the chair of FIG. 1 shown in the first position.

FIG. 6 is a top view of the chair of FIG. 1 shown in the first position.

FIG. 7 is a bottom view of the chair of FIG. 1 shown in the first position.

FIG. 8 is a perspective view of the chair of FIG. 1 shown in a second position.

FIG. 9 is a front view of the chair of FIG. 1 shown in the second position.

FIG. 10 is a rear view of the chair of FIG. 1 shown in the second position.

FIG. 11 is a first side view of the chair of FIG. 1 shown in the second position.

FIG. 12 is a second side view of the chair of FIG. 1 shown in the second position.

FIG. 13 is a top view of the chair of FIG. 1 shown in the second position.

FIG. 14 is a bottom view of the chair of FIG. 1 shown in the second position.

FIG. 15 is a perspective view of a chair according to another embodiment of the design shown in a first position, the embodiment being a mirror image of the embodiment shown in FIG. 1.

FIG. 16 is a front view of the chair of FIG. 15 shown in the first position.

FIG. 17 is a rear view of the chair of FIG. 15 shown in the first position.

FIG. 18 is a first side view of the chair of FIG. 15 shown in the first position.

(Continued)

FIG. 19 is a second side view of the chair of FIG. 15 shown in the first position.

FIG. 20 is a top view of the chair of FIG. 15 shown in the first position.

FIG. 21 is a bottom view of the chair of FIG. 15 shown in the first position.

FIG. 22 is a perspective view of the chair of FIG. 15 shown in a second position.

FIG. 23 is a front view of the chair of FIG. 15 shown in the second position.

FIG. 24 is a rear view of the chair of FIG. 15 shown in the second position.

FIG. 25 is a first side view of the chair of FIG. 15 shown in the second position.

FIG. 26 is a second side view of the chair of FIG. 15 shown in the second position.

FIG. 27 is a top view of the chair of FIG. 15 shown in the second position; and,

FIG. 28 is a bottom view of the chair of FIG. 15 shown in the second position.

Portions of the chair shown in broken lines are for illustrative purposes only and form no part of the claimed design.
